UNITED STATES PATENT OFFICE.

ORIE E. VES SELLS, OF DETROIT, MICHIGAN.

REFRIGERATING APPARATUS.

1,272,735.

Specification of Letters Patent. Patented July 16, 1918.

Application filed July 16, 1917. Serial No. 180,697.

To all whom it may concern:

Be it known that I, ORIE E. VES SELLS, a citizen of the United States of America, residing at Detroit, in the county of Wayne 5 and State of Michigan, have invented certain new and useful Improvements in Refrigerating Apparatus, of which the following is a specification, reference being had therein to the accompanying drawings.

10 This invention relates to a refrigeratory apparatus, and the primary object of my invention is to provide a thermostatically controlled apparatus that may be used in connection with an ordinary refrigerator by placing the expansion coil of the apparatus in the compartment of the refrigerator which ordinarily receives ice, and my apparatus may be located in proximity to the refrigerator or at some point remote therefrom.

20 Another object of my invention is to provide novel electrically operated valves in connection with the switch and controlled by a thermostat so that the apparatus may be automatically started and stopped, and in this manner a uniform or predetermined temperature may be maintained within a refrigerator or other compartment.

A still further object of my invention is 30 to provide a refrigeratory apparatus wherein the parts are constructed with a view of reducing the cost of manufacture and at the same time retain those features by which safety, durability and ease of assembling are secured. With such ends in view, my invention resides in the novel construction, combination and arrangement of parts to be hereinafter specifically described and then claimed.

40 Reference will now be had to the drawings, wherein—

Figure 1 is a front elevation of the refrigeratory apparatus in connection with a refrigerator;

45 Fig. 2 is a diagrammatic view of the electrical devices and thermostat adapted for automatically controlling the operation of the apparatus, and

Fig. 3 is a vertical sectional view of the 50 principal parts of the apparatus.

In the drawings, the reference numeral 1 denotes a stand or support and suitably mounted thereon is a tank 2 containing a condenser coil 3, said coil having the lower 55 convolution thereof tapped through the top of the stand or support 1 to communicate

with a basin 4 suspended from the top of the stand.

The top of the tank 2 is closed by the face 5 of a compressor consisting of a crank case 60 6, a cylinder 7, and a cap 8.

Journaled in the crank case 6 of the compressor is a crank shaft 9 provided with a large sprocket wheel 10 and a connecting rod 11 to a piston 12 reciprocable in the cylinder 7 of the compressor.

65 The cap 8 contains a large gravity, inwardly opening check valve 13 and connected to said cap 14 is the upper convolution of the condenser coil 3.

70 The tank 2 is in communication with a suitable supply of water by a pipe 15 and on said pipe is a valve 16 controlling the supply of water to the tank. The valve 16 is of the gate type and is adapted to be 75 opened and closed through the medium of a solenoid 17 having its core 18 connected to the stem of the valve 16. The pipe 15 is also provided with a connection 80 for an electro-diaphragmatic device 81 and electrical contact members 82 adapted to be held normally in contact by the pressure of water in the pipe 15. This device constitutes means for causing a cessation in the operation of the apparatus, should the supply of 85 water be accidentally shut off. The tank 2 has an overflow pipe 19 and water may be easily circulated through said tank around the condenser coil 3.

80 The bottom of the basin 4 has an opening and a valve seat 20 in communication with a pipe 21 provided with a regulating valve 22, and said valve is connected by a pipe 23 to an expansion coil 24 located within a refrigerator 25 or other compartment. 95 The expansion coil 24 is connected by a pipe 26 to an annular intake port 27 of the compressor cylinder 7.

90 In the basin 4 are spiders 28 supporting a valve 29 adapted to close the opening 20 in 100 the bottom of the basin. The valve 29 is normally seated by the expansive force of a coiled spring 30 encircling the said valve between the upper spider 28 and frame 31 forming part of said valve.

105 Journaled in the side walls of the basin 4 and extending through the frame 31 is a cam shaft 32 provided with a cam 33 within the frame 31 adapted to unseat the valve when said cam shaft is partially rotated. An end of the cam shaft has a fixed crank 34 and the outer end of said crank

is loosely connected to the core 35 of a solenoid 36.

On the stand 1 or in proximity to the sprocket wheel 10 is an electric motor 37, and 5 trained over the sprocket wheel 10 is a sprocket chain 38 operated by the motor for imparting movement to the crank shaft 9 of the compressor.

The base 5 of the compressor is provided 10 with a bracket supporting a casing 39 and within said casing are certain electrical devices controlling the operation of the motor 37 and the energizing of the solenoids 17 and 36. These devices are controlled by a thermostat 40 located in the refrigerator 25 and said thermostat may be in the form of an arm 41 adapted to engage contacts 42 and 43. The arm 41 may be made of two pieces of dissimilar metal or material so that a low 15 temperature will flex the arm in one direction and a high temperature flex the arm in an opposite direction. The contact 43 is connected by a wire 44 to an electro-magnet 45 within the casing 39 and said electro-magnet is connected by a wire 46 and a wire 20 47 to a lead-in wire 48 from a suitable source of electrical energy. The lead-in wire 48 is connected to the electro-diaphragmatic device 81 and said device by a wire 83 to the 25 motor 37 and said motor by a wire 49 to a contact 50 within the casing 39. Associated 30 with the contact 50 is another contact 51 to which another lead-in wire 52 is connected and the contacts 50 and 51 are adapted to be 35 bridged by a cross head 53 on the core 54 of a solenoid 55. The solenoid 55 is connected to the lead-in wire 52 and also to a contact 56 normally engaged by an arm 57 carried by fulcrumed contact members 58 40 and 59. The contact member 59 normally engages the electro-magnet 45 and the other contact member 58 is adapted to engage an electro-magnet 60 in proximity to the electro-magnet 45. The electro-magnet 60 is connected to the wire 46 and by a wire 61 to the 45 contact 42.

The solenoid 17 is connected by wires 62 to the wires 48 and 49, and the solenoid 36 is connected by a wire 63 to the wires 62. 50 The basin 4 has a filling or charging connection 64, and assuming that the apparatus is sufficiently charged with ammonia, the regulating or expansion valve 22 properly set, the valves 16 and 29 open, and the motor 55 in operation, ammonia gas from the expansion coil 24 entering the cylinder 7 of the compressor is compressed into the condenser coil 3 and as the ammonia gas condenses, the liquid ammonia either in the basin 4 or 60 the pipe 21 is forced toward the expansion coil and the circulation continues until a desired low temperature is obtained within the

refrigerator or compartment 25. When a low temperature has been obtained, the arm 41 is affected thereby and engages the contact 42. With the arm 41 connected by a wire 65 to the lead-in wire 52, it is apparent 65 that the electro-magnet 60 will be energized to attract the contact member 58 and when said contact member is shifted, the contact 70 member 59 is moved out of engagement with the electro-magnet 45 and the arm 57 out of engagement with the contact 56. The solenoids 17, 36 and 55 will be deenergized and the cross head 53 will drop by gravity and 75 break the circuit to the motor 37, causing a cessation in the operation of the compressor. The valves 16 and 29 will be closed, shutting off the supply of water to the tank 2.

Immediately upon the temperature rising 80 in the refrigerator 25, the arm 41 again engages the contact 43 establishing a circuit which opens the valves 16 and 29 and places the motor 37 in operation.

It is thought that the operation and utility 85 of my invention will be apparent without further description, and while in the drawing there is illustrated a preferred embodiment of the invention, it is to be understood that the structural elements are susceptible 90 to such variations and modifications as fall within the scope of the appended claims.

What I claim is:—

1. In a refrigeratory apparatus having a condenser coil and an expansion coil, a basin 95 interposed between said coils and adapted to establish communication therebetween, a spring pressed normally closed valve in said basin shutting off said basin to the expansion coil, a cam shaft in said basin adapted for 100 opening said valve, a solenoid switch outside of said basin and adapted for actuating said cam shaft, and thermostatic means controlling the operation of said solenoid switch.

2. In a refrigeratory apparatus having a condenser coil and an expansion coil, a basin interposed between said coils and normally 105 in communication with the condenser coil and adapted to communicate with the expansion coil, a spring pressed valve stem in 110 said basin normally shutting off said basin to the expansion coil, a frame carried by said valve stem, a cam shaft extending through said frame and having a cam therein adapted for raising said valve stem, and electrically 115 operated and controlled means actuating said cam shaft.

In testimony whereof I affix my signature in the presence of two witnesses.
